FIG.4

FIG.5

FIG.6

FIGURE 1 is a perspective view of one chair with attached writing surface panel embodying our new design; FIGURE 2 is a front elevational view thereof;

FIGURE 3 is a side elevational view thereof;

FIGURE 4 is a rear elevational view thereof;

FIGURE 5 is a bottom plan view thereof; and

FIGURE 6 is a perspective view of another chair with attached writing surface panel embodying our new design. The article shown in FIGURE 6 is the same as the article shown in FIGURES 1-5 with the exception that the FIGURE 6 legs are tapered adjacent their lower ends, whereas the FIGURES 1-5 legs are substantially straight.

The dominant features of our design reside in those portions shown in full lines in the drawings.

We claim:

The ornamental design for a chair with attached writing surface panel, substantially as shown and described.
